UNITED STATES PATENT OFFICE.

RAPHAËL NETTER, OF NEW YORK, N. Y., ASSIGNOR, BY MESNE ASSIGNMENTS, TO THE
GENERAL PUMP APPLIANCE COMPANY, A CORPORATION OF NEW YORK.

DEVICE FOR REFACING VALVE-SEATS.

Specification of Letters Patent.

Patented June 8, 1909.

No. 924,369.

Application filed November 14, 1908. Serial No. 462,543.

To all whom it may concern:

Be it known that I, RAPHAËL NETTER, a citizen of the Republic of France, residing at New York city, in the county and State of New York, have invented certain new and useful Improvements in Devices for Refacing Valve-Seats, of which the following is a full, clear, and exact description.

The invention, subject of this application, 10 is an improvement in devices of the general character described and claimed in an application filed by Harry S. Clark and myself on August 10, 1907, Serial No. 387,976, and consisting of an instrument for refacing the 15 valve seats of power pumps and similar devices, and which is adapted to be introduced into the pump casing and mounted for operation upon the valve seats, whereby the latter, when worn, may be refaced or trued 20 up without removal from the pump, or the dismemberment of the pump itself.

The invention resides in improvements in the construction of such devices by means of which a greater economy of operation, a 25 wider range of usefulness, and a more perfect working of the apparatus are secured, but as these improvements reside largely in details of construction they may be most readily understood from the following description with its references to the drawings.

In these latter, Figure 1 is a view in side elevation of my improved refacing device shown as applied to a valve seat. Fig. 2 is a plan view of the under side of the device 35 with the central supporting stem or spindle in section. Fig. 3 is a central vertical section of the same as shown in Fig. 1. Fig. 4 is a horizontal sectional plan view on line $x-x$ of Fig. 3. Fig. 5 is a top plan view of 40 the central portion of the instrument. Fig. 6 is a view in elevation of the supporting stem detached from the device. Fig. 7 is a 45 sectional detail of a cutting tool and means for supporting the same. Fig. 8 is a view in elevation of a gage for adjusting the cut of the tool.

Corresponding parts in the several figures are designated by the same numerals.

It may be stated, before proceeding to a 50 description of the improvement, that in the operation of power pumps it becomes necessary at intervals, more or less frequent according to the extent and nature of their

use, to reface the valve seats, for which purpose it has been heretofore generally necessary to remove the casing or sides of the pump chambers, as it is difficult if not impossible to detach and replace the valve seats by working through the usual hand holes which are provided in the casing to afford 55 access to the interior of the pump. In ordinary pump construction a stem is screwed centrally into each valve seat, to serve as a support and guide for the valve, and in practicing this invention, these stems are removed by any suitable tool introduced through the hand holes, and the stem for carrying my improved refacing device inserted in each valve seat successively. The 60 device when thus applied to a valve seat is 65 operated by any suitable motor to effect the proper refacing of the seat.

The stem 1 for supporting the instrument which I employ is shown in Fig. 6 as provided at its lower end with a threaded portion by means of which it is screwed 75 into the central socket of a valve seat 2, after the valve stem has been removed therefrom. Upon this stem the refacing device is mounted, and while the detailed construction of these devices may be very greatly varied, their most practical embodiment, so far as now known to me, is that illustrated 80 in the drawings. Referring now to Figs. 1 and 3, the numeral 3 designates a disk or 85 plate to the upper face of which is secured a bevel gear plate 4, and to the under side of which are secured the cutters and their appurtenances. Secured also to the plate 3 is a casting 13 (see Figs. 3 and 4), forming 90 a chamber immediately above the bevel gear plate 4, in which are located the wheels 14, 15 and 16, of a planetary gear system, the said wheel 16 surrounding the stem 1. The spindles of the gear 14 and 15, extend down 95 through the plates 4 and 3 and carry worm wheels 17, 18 engaging with corresponding pinions 19, 20, that are mounted on threaded shafts 21 and 22, passing through and in threaded engagement with the blocks or 100 carriages 23, 24 that carry the cutters 25, 26, and slide in guides 27, 28 attached to the under side of plate 3.

The casting 13, secured to and supporting all of the elements above enumerated, has a 105 sleeve or tubular extension 13^a surrounding

the stem 1, which sleeve is free to turn about the said stem and is rotatably connected with or virtually suspended from the fixed or non-rotating portion of the instrument; 5 which non-rotating portion constitutes in effect a base and comprises the casting 29 and the other connected parts to be herein-after described more in detail.

Surrounding the casting 13 and over the 10 gear chamber formed thereby is a casing 12, which normally turns freely about said casting 13, but which may be held in fixed relation to the stem 1 in any horizontal angular position by the engagement of a spring-actuated bolt 30 carried in a suitable socket, with any one of a series of recesses 31 in a sleeve 32, attached to the casting or ring 29 and hence fixed with reference to the stem 1.

The casing 12 is formed or provided with 20 a horizontal bearing or journal 12^a for a sleeve 11 having an extension 11^a affording a bearing for a spindle 9 containing a socket or other equivalent means for the attachment of a driving shaft 10. The spindle 9 carries a bevel gear wheel 8, meshing with a bevel gear wheel 7, on one end of a short shaft or spindle 6 passing through the sleeve 11, and carrying a second bevel gear 5, beyond which the end of the spindle 30 finds a bearing in the casing 12.

The gear wheel 5 meshes with the bevel gear 4 whereby a system of gearing is provided for imparting the rotation of the shaft 10 to the plate 3.

35 To facilitate an understanding of the nature and purpose of the parts above described, and constituting the main features of improvement characterizing the apparatus, the operation of the same will be briefly described.

Assuming the instrument to have been assembled with its parts in the relation shown, and introduced into a pump casing through one of the hand holes, the stem 1 is then 45 inserted in the socket of a valve seat in place of the valve stem and a flexible shaft 10 from any suitable motor, not shown, passed in through the hand hole and connected with the spindle 9. The casing 12 is 50 then turned to bring the spindle 6 to the most convenient position horizontally, and fixed in such position by the engagement of the bolt 30 with the proper recess or indentation 31 in sleeve 32. The sleeve 11 is then 55 rotatably adjusted to bring the spindle 9 to the angular position most convenient for operation and fixed in such position by clamping screws 33. The plate 3 is then 60 adjusted vertically, by means to be described, to secure the proper depth of cut of the tools 25, 26, and the latter are set in position close to the stem 1. The motor being then started in operation, the rotation of its 65 shaft is imparted through the system of bevel gears to the plate 3, and the cutting

tools thereby caused to travel around the stem 1. This rotation of the plate 3 and its attached parts, imparts a rotary movement to the screw shafts 21, 22, and hence a slow longitudinal movement thereon of the 70 blocks or carriages 23, 24, through the system of planetary gears, the wheel 16 of which is keyed to the fixed stem 1, so that the cutters 25, 26, describe a spiral path over the valve seat and reface or true the same 75 to a perfectly level surface.

To meet the requirements of practical operation in the general use of the instrument, I have devised certain attachments and details of construction which will now 80 be described. In the first place it is desirable, in order that the construction of different sizes of the device for valve seats of different diameters may be avoided, as far as possible, that provision be made for substituting in the same instrument plates 3 of various diameters, carrying cutters of corresponding range of radial feed. To this end the plate 3 is secured to the casting 13 by screws 34, access to which for purpose 85 of insertion or removal is afforded through an opening in the casing 12, which is normally closed by a screw plug 35. The worm wheels 17, 18 are also made readily detachable from their spindles, which pass freely 90 through the plates 3 and 4, as by means of locking screws 36. Again, as the instrument is intended for use inside a pump casing, and in general, under conditions where its adjustment and operation cannot be readily 95 observed, I make the following provision for throwing the cutters out of gear, when by the reversal of the motor they are brought fully up to their initial position close to the stem 1.

The stem 1 is hollow, and through it extends a stem or plunger 37, having a head 38, and carrying a crosspiece 40 extending through a slot in the stem 1 and serving as a key to couple the gear wheel 16 to the 100 stem 1. Between the plunger 37 and the stem 1 is a spiral spring 39 in an enlargement of the bore of the former, one end of which is connected to the head 38, and the other to the stem 1. This spring exerts a 105 tendency to raise the plunger and to turn it in a predetermined direction. Normally, therefore the plunger would be held in its raised position and the key 40 lifted out of engagement with the gear wheel 16, were it 110 not for the device illustrated in Fig. 6. This consists of a stud or projection 41 on the plunger 37, which projects through a slot 42 in the stem 1. On one side of the slot and near the lower end thereof is a shoulder with 115 which the stud 41 engages when the plunger 37 is depressed. The spring 39 imparts a rotary tendency to the plunger 37 that maintains this engagement when once made.

When the cutters are fed in toward the 130

center of the plate 3, for adjusting them to their initial position, a set screw 49 (see Fig. 2) carried by one of the tool carrying blocks will come into engagement with the end of the stud 41 just before the cutters themselves come in contact with the stem 1 and throw said stud out of engagement with its shoulder, as indicated by the arrow in Fig. 6. The force of the spring 39 will 10 instantly lift the plunger 37 and withdraw the key 40 from the gear wheel 16, so that the latter is free to rotate and no further feed movement will be imparted to the cutters until the plunger is again depressed and the 15 stud 41 brought into engagement with its shoulder. This latter operation is effected by hand when the motor is ready to be started in the direction for operating the cutters.

20 To facilitate the insertion, removal and adjustment of the cutting tools the following devices are used: Guides are provided for the tool carriages consisting of plates 43, 28, 44 and 27 secured to the underside of the 25 plate 3. One of each pair of these plates, as 27 or 28, is attached to the plate 3 by screws 45 and carries one or more set screws 46 along its outer edge, the ends of which bear against the under surface of plate 3. 30 The tool carriages or slides are blocks of steel 23, 24, with dove-tail portions contained within the grooves of corresponding shape formed by the said plates. The threaded 35 extensions of the shafts 21, 22, pass through these blocks as above explained.

A recess is formed in each block in which a cutter is inserted, and these latter are clamped in position by blocks 47, (see Fig. 2), held against the carriages by screws 48. 40 By loosening screws 45, tightening up screws 46 slightly, and then tightening screws 45, the inner edge of the plate 43 will be thrown slightly forward to prevent or take up any lost motion of the tool carriage 45 due to wear or other cause.

It being essential to the proper operation of the instrument that all play or lost motion of the rotary parts carrying the cutters should be avoided, while at the same time 50 ready means for vertically adjusting such parts should be at hand, I have devised the following devices for effecting these purposes.

The upper portion of the vertical or sleeve-like portion 13^a of the casting 13 is reduced in external diameter, leaving a shoulder immediately above which the said sleeve, for a short distance, is externally threaded, as shown. Over this threaded portion an internally threaded ring or washer 50 is screwed tight against the said shoulder. The 60 ring or casting 29 is reamed out to form an annular space or chamber around the upper end of the sleeve 13, and the upper portion 65 of the ring is threaded both inside and out.

The lower portion of the annular space between the sleeve 13 and ring 29 is filled by the washer 50, and over this latter a washer 51, externally threaded to engage with the ring 29, is inserted and occupies the remaining portion of the said annular chamber. 70

The ring 32 heretofore referred to, is internally threaded at its lower end and is screwed down over the upper externally threaded part of the ring 29. At its upper end this ring 32 has an internal flange or shoulder, and fitted into the opening is an annular cap or cover 56, to which is secured by screws 54 a ring 53, having an upwardly extending flange 58 threaded inside to engage with corresponding threads on the upper end of the stem 1.

The cap 56 and ring 53 thus become virtually one piece, in threaded engagement with the stem 1, but rotatable with respect to the 85 ring 32 and the ring 29, which latter are united as in one piece by their threaded engagement with each other. By turning the cap 56, therefore, ring 29 and all parts of the instrument secured thereto are raised or lowered on stem 1. The adjustment of the cut is thus effected. As, however, it is necessary that rings 32 and 29 should not turn about the stem 1 when the instrument is in 95 operation, and since it is desirable that they should not do so during the adjustment referred to, a washer 52 with two inwardly extending lugs to engage with vertical grooves 62 in the threaded portion of stem 1 is introduced in the ring 32 and clamped thereto as 100 by set screws 63. In order to further secure a fixed relation after adjustment between the rings 32 and 29, and the stem 1, the flange 58 of ring 53 (see Fig. 5) is provided with vertical saw cuts 60 and is screwed down 105 over the upper end of the stem 1. This leaves an annular recess in the cap 56, threaded on its inner wall, and into this is inserted a washer 55 internally threaded and provided with a saw cut 59, and slightly tapered 110 on the outer surface to conform to a similar configuration of the inner surface of the cap 56. Said cap is, furthermore, provided with two diametrically opposite saw cuts 57.

When the washer 55 is screwed home it 115 contracts the flange 58 on stem 1, and expands the annular cap 56 against ring 32, and effects a firm union between said ring and the stem 1. When the washer 55 is loosened, the cap 56 may be turned, raising 120 or lowering ring 32 and its attached parts, but not rotating them because of the engagement of washer 52 with stem 1.

The number of parts described as comprising the instrument will be seen, upon a 125 consideration of the purpose and function of the devices last referred to, to be necessary in this particular form, but the same results of course might be obtained by modifications of the form illustrated.

It will be further observed that by the construction described the rings 29 and 32, with reference to which the casting 13 and its attached parts are free to turn, are not

5 only securely fixed to the stem 1, but are capable of being drawn up tightly against the washer 50 which may be regarded as integral with casting 13, and all lost motion or play between these two elements, the fixed

10 and rotary portions of the device, prevented.

In order that the cap 56, when turned to any desired position may be temporarily secured to the ring 32, a spring latch 63^a, 15 pivoted to ring 32 by one of the set screws 63 and adapted to engage with notches 64 in the edge of the cap 56, may be employed.

In Figs. 1 and 8, I have shown a gage by means of which the rough adjustment of the

20 instrument may be effected after it has been set over a valve seat inside of a pump. This device consists of a block of metal 65 having a groove 66 to adapt it to be placed over the edge of the plate 3 and secured thereto by a set screw 67.

25 Working vertically in the block is a stem with a foot 68 that may be adjusted to any desired height and fixed by a set screw 69. In using the device the gage is applied to the plate 3, as shown, and the latter lowered by turning the cap 56 until the foot 68 rests on the face of the valve seat. The gage is then removed and the cap 56 turned through a known angle to secure the desired depth of cut.

30 It is obvious that the device as illustrated 35 may be modified in many particulars without departure from the invention. I have for example shown two cutters, but it is obvious that one of these may be omitted and the device modified accordingly. These 40 and similar modifications will however suggest themselves readily to a skilled mechanic.

Having thus described my invention, what I claim is:

1. An instrument for refacing the valve 45 seats of pumps and similar devices, comprising in combination a stem or spindle adapted for fixed attachment to a valve seat, a rotatable carrier mounted thereon, a cutting tool supported by said carrier, a base adapted to be fixedly secured to the stem, gearing carried thereby for imparting rotation to the carrier, and means carried by the carrier and dependent for operation on the rotation thereof, for shifting the position of the cutting tool, so that it describes a spiral path over the face of the valve seat.

2. An instrument for refacing the valve 50 seats of pumps and similar devices, comprising in combination a stem or spindle adapted for fixed attachment to a valve seat, a rotatable carrier mounted and capable of vertical adjustment thereon, a cutting tool supported by said carrier, a base adapted to be fixedly but detachably secured to the stem, gearing carried thereby for im-

parting rotation to the carrier, and means carried by the carrier and dependent for operation on the rotation thereof for shifting or feeding the cutting tool horizontally, as set forth.

3. In an instrument for refacing the valve 70 seats of pumps and similar devices, the combination with a stem or spindle adapted for fixed attachment to a valve seat, of a part rotatable thereon, and a part adapted to be 75 fixedly secured thereto and serving as a base, a cutting tool carried by the rotating part, gearing intermediate to the base and rotating part for imparting rotation to said rotating part, and gears carried by the rotating part so intermediate to the tool and stem for shifting or feeding the tool horizontally, as set forth.

4. In an instrument for refacing the valve 85 seats of pumps and similar devices, the combination with a stem or spindle adapted for fixed attachment to a valve seat, of a part constituting a base, and a tool carrier rotatably connected to and supported thereby, means for fixedly securing the base to the 90 stem, means for simultaneously adjusting the base and the rotating tool carrier vertically with respect to said stem, and gearing intermediate to the base and carrier for 95 rotating the latter.

5. In an instrument for refacing the valve 95 seats of pumps and similar devices, the combination with a stem or spindle adapted for fixed attachment to a valve seat, of a tool carrier rotatably mounted on said stem, a 100 casting detachably secured to the stem, an intermediate sleeve supporting the tool carrier and rotatable around the stem, gearing carried thereby by means of which rotation is imparted to the carrier, and means for 105 uniting the rotatable sleeve to the fixed casting and taking up lost motion between the same, as set forth.

6. In an instrument of the kind described, 110 the combination with a stem or spindle adapted for fixed attachment to a valve seat, of a part constituting a base adapted to be fixedly secured to the stem, a rotating tool carrier, a horizontally adjustable part intermediate to the base and tool carrier, means 115 for maintaining the base and intermediate part in close engagement, gearing carried by the intermediate part for imparting rotation to the tool carrier, and a coupling for said gearing capable of angular adjustment, 120 as and for the purpose set forth.

7. In an instrument of the kind described, 125 the combination with a stem or spindle, adapted for fixed attachment to a valve seat, of a part supported on and adapted to be fixedly secured to the stem and constituting a base, a tool carrier, an intermediate part rotatably suspended from the base and supporting the tool carrier; means for locking the said intermediate part to the base in 130

various positions of horizontal adjustment, and gearing on said intermediate part for imparting rotation to the tool carrier, as set forth.

5. 8. In an instrument of the kind described, the combination with a stem adapted for fixed attachment to a valve seat, of a part adapted to be fixedly secured to the stem and constituting a fixed base, a tool carrier rotatably supported on the base, means for taking up lost motion between the base and tool carrier to maintain the same in close engagement, and gearing on the base engaging with a gear on the tool carrier for imparting rotation to said carrier, as set forth.

9. In an instrument of the kind described, the combination with a stem adapted for fixed attachment to a valve seat, of a base secured to the stem, a rotating carrier, a cutting tool carried thereby, gearing for imparting rotation to the carrier and shifting the tool horizontally, means for connecting said gears in operative relation, and a stop movable horizontally with the cutting tool, adapted to encounter means at a given point in its travel for throwing said gears out of operative relation, as set forth.

10. In an instrument of the kind described, the combination with a non-rotating supporting stem, a carrier rotatable thereon, and means for rotating the carrier, of a tool slide mounted on said carrier and capable of radial movement thereon; mechanism for actuating said tool slide, including a driving gear on said stem; a movable key for locking the gear to the stem, and means, actuated by the tool slide when retracted to a predetermined inner position, for releasing the key and freeing the gear from its non-rotating connection with the stem; as set forth.

11. In an instrument of the kind described, the combination with a fixed supporting stem, a carrier rotatable thereon, and means for rotating the carrier; of a tool slide mounted on the carrier, a non-rotating gear on the supporting stem, a planetary gear journaled in the rotatable carrier and meshing with the non-rotating gear, a screw shaft working in the tool slide to shift the same radially of the carrier, and means connecting the planetary gear with the screw shaft to rotate the latter; as set forth.

12. In an instrument of the kind described, the combination with a fixed supporting stem, a carrier rotatable thereon, a tool slide movable radially on the carrier, and means for shifting the tool slide, said means including a driving gear on the stem, and a planetary gear meshing therewith; of a movable key for locking said driving gear to the stem, a rod slidably mounted in the stem to shift the key, yielding means tending to op-

erate the rod to release the key, and a device 65 normally maintaining the rod and key in locking position, said device being in position to be engaged and released by the tool slide at a predetermined point in the latter's line of travel toward the supporting stem; 70 as set forth.

13. In an instrument of the kind described, the combination with a fixed supporting stem, a tool carrier rotatable thereon, and a bevel gear mounted on the carrier; of a 75 member rotatably adjustable about the supporting stem, means for securing the said member in adjusted position, a driving bevel gear journaled in said member and meshing with the first mentioned bevel gear, a device 80 rotatably adjustable about the axis of the driving bevel gear, means for securing said device in adjusted position, and means carried by said device for transmitting 85 power from a motor-driven shaft to the driving bevel gear; as set forth.

14. In an instrument of the kind described, the combination with a fixed supporting stem, a tool carrier rotatable thereon, and a bevel gear mounted on the carrier; of a 90 member rotatably adjustable about the stem, a shaft extending radially with respect to said bevel gear, a supporting device rotatably adjustable about said shaft, a bevel gear journaled in said device, a bevel gear 95 on said shaft and in mesh with the last mentioned bevel gear, a bevel gear on said shaft and in mesh with the bevel gear on the tool carrier, and means for connecting a power-driven shaft to the bevel gear journaled in 100 the said supporting device; as set forth.

15. In an instrument of the kind described, the combination of a fixed supporting stem, a rotatable tool carrier axially adjustable thereon, means for securing the carrier 105 in adjusted position, a member rotatably adjustable about said stem, means for locking said member in adjusted position, and driving mechanism carried by the said member 110 for rotating the tool carrier; as set forth.

16. In an instrument of the kind described, the combination with a fixed supporting stem, of a chambered member having a tubular neck encircling the stem and adjustable axially thereon, a tool carrier connected to 115 and supported by the chambered portion of said member, a removable ring or washer on said tubular neck, an axially adjustable member surrounding the stem and having a flange extending under the ring or washer, 120 and means for securing the flanged member in adjusted position on the stem; as set forth.

17. In an instrument of the kind described, the combination with a fixed supporting stem, of a chambered member having a tubular neck encircling the stem and axially adjustable thereon, means for securing said 125 member in adjusted position but permitting

6
rotation thereof, a tool carrier fixed to the chambered portion of said member, a gear in fixed relation to the stem inside the chamber of said member, a planetary gear within the chamber and in mesh with the fixed gear, a tool slide on said tool carrier, means actuated by the planetary gear for shifting the tool slide, and means for rotating the tool

carrier and the chambered member about the supporting stem; as set forth.

In testimony whereof I affix my signature in the presence of two subscribing witnesses.
